UNITED STATES PATENT OFFICE.

FREDERICK W. TUERK, JR., OF SYRACUSE, NEW YORK, ASSIGNOR TO THE TUERK WATER METER COMPANY, OF SAME PLACE.

HOSE-CO尤LING BAND.

SPECIFICATION forming part of Letters Patent No. 366,532, dated July 12, 1887.

Application filed February 2, 1887. Serial No. 226,263. (No model.)

To all whom it may concern:

Be it known that I, FREDERICK W. TUERK, Jr., of Syracuse, in the county of Onondaga, in the State of New York, have invented new and useful Improvements in Hose-Coupling Bands; of which the following, taken in connection with the accompanying drawings, is a full, clear, and exact description.

My invention relates to improvements in bands for hose-couplings, which are clamped over the hose to secure the coupling therein, and the object is to provide an efficient and simple device which will evenly clamp the hose onto the coupling and securely retain the same in position; and to this end my invention consists in a band of metal, either cast or struck up, formed with its central portion straight and its ends curved, so that it may be readily bent into form without weakening the ends, and in strengthening the same by providing ribs on the edges of the band, and extensions oppositely located on the respective ends, and in providing the ends with recessed and countersunk apertures for the passage of the clamping-bolt.

It consists, also, in the detail construction and arrangement of the parts, all as hereinafter more fully described, and pointed out in the claims.

In specifying my invention reference is had to the accompanying drawings, in which, like letters indicating corresponding parts in all the views, Figure 1 is a top plan of the blank from which my improved band for hose-couplings is formed. Fig. 2 is an isometric view showing the under side of the blank and the curved ends provided with the oppositely-arranged extensions. Fig. 3 is an isometric view of the blank bent up in shape and provided with the clamping-screw, illustrating particularly the shape of the recess which holds the nut of the clamping bolt or screw. Fig. 4 shows the device applied to the hose, clamping the coupling in position. Fig. 5 is a transverse section taken on line $\alpha\alpha$, Fig. 3. Fig. 6 is a side view of a hose and coupling with the band in place thereon.

A represents the blank from which my improved band for hose-couplings is formed, and the same may be struck up or cast of suitable

metal which will permit the same to be bent into form, as presently explained.

The blank A has a straight central portion, B, Fig. 2, and curved ends C C, and is provided with the ribbed edges $a a$, Fig. 1, $b b$, Fig. 2, and with the oppositely-arranged extensions E E, Fig. 2, and the ends D D, Figs. 1 and 2.

The ribs $a a$ $b b$ are provided to strengthen the blanks when bent into form, and the curved ends C C are provided in order that when the blank is bent in shape the bend comes on the straight portion B, thereby permitting the blank to be shaped without weakening the ribbed ends C C.

The ribs $a a$ on the curved ends C C of the band are made flaring at a' from the central straight portion, B, of the band A, the flaring ribs terminating at the top or upper extremity of the lugs D when the band is formed into shape. The object of thus flaring the ribs is to impart great strength and stiffness to the lugs D with the minimum quantity of metal at this point, and the desired result is thereby secured, as the curved ends are unaffected by bending the band into shape, while the flaring ribs serve as a brace or tie against the draw of the clamping-bolt in clamping the band on the hose L to secure the coupling therein.

The ribbed ends C C D D form lugs when the blank is bent in shape, as best shown in Figs. 3 and 4, and one of said lugs, D, has a recess, g' , between the flaring ribbed edges $a' a'$, into which the nut of the clamping-bolt G is inserted and held by the flaring ribbed edges $a a$, to hold the nut when the bolt is turned to clamp the band onto a hose and coupling. The opposite lug, D, is provided with the countersunk hole f for the head I, Fig. 4, of the clamping-bolt G.

The extensions E E, as will be observed, are located on opposite edges of the ends D D of the blank, and when the blank is shaped the said extensions E E form tongues which lap into the opposite bend of the band and form a continuous circular clamp, which is rendered adjustable or compressible by tightening up or unscrewing the clamping-bolt G.

The object of providing the projecting tongues E is to provide means for compress-

ing the material of the hose L uniformly, and thus evenly clamping the hose to the coupling.

In all of the bands for hose-couplings now used no provision is made for this purpose, and the band clamps the hose L to the coupling and squeezes the material of which the hose is composed into a fold between the two jaws or lugs of the clamp, thereby straining the hose out of shape and weakening the same without securely holding the coupling in place; and by frequently tightening and loosening the band the end of the hose becomes frayed out and destroyed, rendering it necessary to cut off the end.

The main difficulty in the use of the old band results from the insecure and uneven clamping of the hose to the coupling. My invention remedies this defect, for the reason that the extensions E E bear against the hose from opposite sides and exert the pressure equally thereon, so as to tighten or compress the material circumferentially and evenly clamp the hose to the coupling. Furthermore, the old band for hose coupling is necessarily weak at the clamp, for the reason that the clamp-screw compresses the lugs at the point farthest from the circumference of the coupling, and the tendency is to break the lugs off, while in my improved band the extensions E E pass under the opposite bends of the band A and underneath the lugs D D, thus affording a circumferential hold entirely around the hose, strengthening and stiffening the lugs, so that the clamp-screw compresses the band evenly without twisting, and thereby weakening the lugs in the operation.

It will be observed that the projecting ribs b b leave a channel or recess in the under side of the band, and the extensions E E slide in the said recess, and are prevented from squeezing out laterally as the band is compressed, the opposite edges serving to guide the extensions within the recess, and forming a wall or flange to prevent the extensions from squeezing out.

The operation of my invention will be readily understood from the foregoing and from a consideration of the drawings.

The blank A is bent in shape on the straight portion B, and the bolt G is provided and the device is applied to the hose L over the coupling N, which is provided with the union M, as shown in Figs. 4 and 6, and the band is clamped securely onto the hose with a screw-driver, the nut H being securely held in the recess g' against the flaring ribbed edges a a, and the band A may be readily removed by loosening the screw-bolt G. The ribbed edges b b serve also to compress the material of the hose 60 against the thread of the coupling N, thus serving to provide a very secure connection of the coupling to the hose.

Having thus fully described my invention, what I claim as new, and desire to secure by Letters Patent, is—

1. As a new article of manufacture, a hose-coupling band formed of metal having oppositely-arranged extensions on its ends interlocking with ribs formed on the inner edges thereof, and a clamp-bolt passing through lugs on the ends of the band to secure the band on the hose-coupling, substantially as and for the purpose set forth.

2. The combination of the band A, having oppositely-arranged projecting extensions E E, ribs b b on inner side adjacent to the extension E, ribs a a on outer side of the band, lugs D D, recess g', for the nut H, and the bolt G, all substantially as and for the purpose set forth.

3. The cast-metal hose-coupling band A, having extensions E E, oppositely arranged on the ends thereof, ribs b b on the inner side of the band, lugs D D on the ends, and strengthening-ribs a a', flaring to the top of the lugs, substantially as and for the purpose set forth.

In testimony whereof I have hereunto signed my name, in the presence of two attesting witnesses, at Syracuse, in the county of Onondaga, in the State of New York, this 31st day 90 of January, 1887.

FREDERICK W. TUERK, JR.
